CLAIM

The ornamental design for an instrument holding device for surgery, as shown and described.

DESCRIPTION

FIG. 1 is a front perspective view of a section of an instrument holding device for surgery according to the present invention.

FIG. 2 is a front view of a section of the instrument holding device for surgery of FIG. 1.

FIG. 3 is a rear view of a section of the instrument holding device for surgery of FIG. 1.

FIG. 4 is a left side view of a section of the instrument holding device for surgery of FIG. 1.

FIG. 5 is a right side view of a section of the instrument holding device for surgery of FIG. 1.

FIG. 6 is a top view of a section of the instrument holding device for surgery of FIG. 1; and,

FIG. 7 is a bottom view of a section of the instrument holding device for surgery of FIG. 1.

The instrument holding device for surgery is shown with symbolic breaks in its length. The appearance of any portion of the article between the break lines forms no part of the claimed design. The dashed lines immediately adjacent to the shaded areas in the figures represent the boundaries of the claimed design. The dashed lines in the figures illustrate the portions of the design that form no part of the claimed design. None of the broken lines form any part of the claimed design.

1 Claim, 7 Drawing Sheets
